US0D1038387S

(12) **United States Design Patent** (10) Patent No.: **US D1,038,387 S**
(45) Date of Patent: ** Aug. 6, 2024

(54) **BAYONET PLUNGER ROD**

(71) Applicant: **NeuroDerm, Ltd.**, Rehovot (IL)

(72) Inventor: **Lior Bar Chen**, Ganei Tal (IL)

(73) Assignee: **Neuroderm, Ltd.**, Rehovot (IL)

(**) Term: **15 Years**

(21) Appl. No.: **29/842,704**

(22) Filed: **Jun. 15, 2022**

(51) LOC (14) Cl. **24-02**

(52) U.S. Cl.

USPC **D24/129**; D24/130

(57) **CLAIM**

The ornamental design for a bayonet plunger rod, as shown and described.

DESCRIPTION

FIG. 1 is a top perspective view of a bayonet plunger rod; FIG. 2 is a bottom perspective view of the bayonet plunger rod.

FIG. 3 is a front view of the bayonet plunger rod;

FIG. 4 is a rear view of the bayonet plunger rod;

FIG. 5 is a right side view of the bayonet plunger rod;

FIG. 6 is a left side view of the bayonet plunger rod;

FIG. 7 is a top view of the bayonet plunger rod; and,

FIG. 8 is a bottom view of the bayonet plunger rod.

The broken lines shown in the drawings illustrate the environment of the claimed design and form no part thereof.

1 Claim, 5 Drawing Sheets
